UNITED STATES PATENT OFFICE.

BERNIE C. KRIDLER AND JAMES C. BOYLE, OF FLINT, MICHIGAN, ASSIGNORS TO THE SHINGLE LOCK COMPANY, OF FLINT, MICHIGAN, A CORPORATION OF MICHIGAN.

SHINGLE ROOF CONSTRUCTION.

Application filed August 23, 1923. Serial No. 658,978.

To all whom it may concern:

Be it known that we, BERNIE C. KRIDLER and JAMES C. BOYLE, citizens of the United States, and residents of Flint, in the county 5 of Genesee and State of Michigan, have invented certain new and useful Improvements in Shingle Roof Constructions, of which the following is a full, clear, and exact description.

10 The invention appertains to certain improvements in shingle roof constructions, and more particularly to a means for facilitating the laying and securing of shingles in position on a roof framing of usual or 15 ordinary construction.

The principal object of the present invention is to provide for a novel form of means as characterized, and one adapted for securing shingles in position on a roof framing 20 in a more rapid and less laborious manner and at a marked saving in cost than has heretofore been possible in the practice, and without the use of driven, headed or screw threaded fastenings as ordinarily employed 25 for the purpose.

Another object of the invention is to provide for a shingle securing means of a simple and inexpensive construction and arrangement, such as may be readily manufactured in quantities at a low cost for material and labor, and which will be easy 30 of application, but otherwise durable and efficient in use.

A further object of the invention is to 35 provide for a means as hereinbefore characterized, and one which not only acts to effectively secure the shingles in position, but also to uniformly gage the exposed or weather portions of the shingles equally in 40 each of the several rows thereof and to maintain the same in properly laid condition at all times throughout the life of the roof.

With the foregoing and other equally important objects in view, the invention resides 45 in the certain new and useful construction and arrangement as will be hereinafter more fully described, set forth in the appended claim, and illustrated in the accompanying 50 drawings, in which:—

Figure 1 is a fragmentary plan view of a shingle roof showing the manner of use of the improved shingle securing means,

55 Figure 2 is a transverse section taken on the line 2—2 of Figure 1, and,

Figure 3 is a plan view of one of the shingles, and showing the manner of modifying a standard form of shingle to adapt the same for the application of the improved fastenings thereto in the securing of the 60 same in position.

Referring to the drawings, wherein similar characters of reference designate corresponding parts through the several views thereof, the numeral 10 indicates a series of furring strips or sheathing boards arranged in a somewhat usually spaced relation, one parallel to the other, and which are secured to roofing rafters (not shown) of the roof framing of a building. These furring strips 65 10 are to have laid thereon the roofing shingles 11 in the usual manner, wherein one row of the shingles overlap adjacent rows thereof, substantially as shown.

For effecting the securing of the shingles 70 11 in position on the furring strips 10, and without the use of nails or the like as heretofore employed for the purpose, the present invention contemplates the use of metal members or clips which are preferably 75 formed from suitable lengths of a relatively heavy wire, and of a design to engage over the upper side edges of the furring strips 10 and to interlock with certain slots and recesses formed in the shingles, all in a manner to be hereinafter fully explained.

Each of the clips are formed to provide a substantially U-shaped body 12 to engage over and grip the upper edge of a furring strip 10 and the adjacent edge portion of a 90 shingle 11 laid on the upper side of the furring strip. The lower leg portion 12^a of the clip is preferably bent slightly inward so as to effect a firm gripping action against the under face of the furring strip, with its free 95 end portion 12^b bent slightly outward at an angle sufficient to facilitate the engagement of the clip over the edge of the said furring strip. The upper leg portion 12^c, of each clip, is preferably of a slightly greater 100 length than the lower leg portion 12^a, and has its free end bent to provide an upwardly and rearwardly inclined hook portion 12^d, which is to be engaged by the lower end edge of a shingle, as will be hereinafter explained.

Each of the shingles 11 will be of standard form and material, but, in the use of the improved fastenings therewith, will have their upper end edges formed with inwardly 110

extending slotted openings 11^a and their lower end edges with small recesses 11^b, the latter being disposed in alignment with the slotted openings 11^a, and both preferably in 5 the plane of the longitudinal center of the shingle. Also, the material at one side edge of each shingle 11 will be cut away, as at 11^c, inwardly from the lower end edge thereof, whereby to provide a slotway between the 10 same and the side edge of an adjacent shingle, substantially as shown in Figure 1. In the construction of a shingle roof in accordance with the present invention, the shingles are to be laid on the furring strips 15 10 after the usual manner, as in successive rows, each row overlapping the other upwardly of the furring strips 10 from the eaves of the roof framing, but instead of the 20 nailing of the shingles in position, such as often results in the cracking or splitting of the same, the clips 12 will be employed to fasten them in position. In the laying of the first row of the shingles 11, a clip will be used for each, and is engaged over the 25 upper edge of the furring strip and in a manner that the connected portion thereof will pass inwardly of the slot 11^a of the corresponding shingle, when the upper leg portion 12^c, of the clip, will overlie the upper face of the shingle in aligning relation with the slot 11^a and the recess 11^b. With the laying of the next succeeding row of shingles, other clips will be applied to the 30 next highest furring strip 10, to secure the upper ends of these shingles, when the hooked ends 12^d of the first of the clips will be engaged at the inner ends of the cutaway portions 11^c thereof. Now, with the laying 35 of the third row of shingles 11, the upper end edges of the same will be secured by clips, after the manner of the previously secured shingles, while the recesses 11^b, in the lower end edges thereof, will be engaged with the hooked ends 12^d, of the upper leg 40 portions 12^c, of the first row of clips 12, when these hooked ends 12^d will be bent over into engagement with the adjacent upper face portions of the shingles to positively 45 secure the lower exposed or weather end portions in position against the upper face 50 portions of the underlying shingles. This method of clipping the upper ends of the shingles 11 of the successive rows thereof direct to the furring strips 10 and securing the lower recessed edge portions of the same by bending into the recesses 11^b the hooked 55 ends 12^d of the second lower row of the clips 12, will be continued until the entire roof framing is covered. It is to be noted that 60 hooked ends 12^d of the clips 12, when bent into the recesses 11^b, in the lower end edges of the uppermost shingles 11, also act to secure the adjacent side edges of the shingles 65 in the underlying rows thereof against curling or buckling, since the uppermost shingle,

engaged by the hooked ends 12^d, are centered over the joint of the adjacent underlying shingles, and the point of engagement of the hooked ends 12^d with the recessed portions 11^b is directly in the plane of the longitudinal center of the uppermost shingle. 70

Thus, it will be seen that, in the use of these clips 12, the shingles 11 will not only be secured in position as hereinbefore indicated and against any and all possible accidental displacement, but also that, after the laying of the first three or four rows of the shingles 11 upward from the eaves of the roof raming, the shingles of one row thereof will be properly gaged into position, or accurately centered over the joints between the shingles of the previously laid rows, by the engagement of the recesses 11^b, in the lower edges of the shingles, with the hooked ends 12^d of the clips of the second row of clips 80 12 below the said edges, as well as by the engagement of the hooked ends 12^d, of the next highest row of the clips 12 at the inner ends of the cutaway portions 11^c, of the shingles, being laid, while the exposed or 90 weather portions of the shingles, in each row, will be of a uniform area throughout the entire roof structure when completed.

In the foregoing method of laying and securing shingles, several advantages are obtained over the prior shingle roof constructions, namely, that the spaces between the furring strips or sheathing boards 10 are completely covered by intermediate portions of the shingles; that there are three thicknesses of the shingles over the entire roof instead of two of such thicknesses in the ordinary constructions; that the number of shingle fastenings are reduced by nearly fifty per cent over the number formerly used; that there is a marked saving in the cost of material and labor; and that there is a corresponding saving in time and money by reason of the fact that more roof space may be covered in a given time than was formerly the case and since shingles of a larger area may be readily and securely fastened in position with the clips applied thereto in the manner as shown and described herein. 100 105 110 115

It will be readily obvious that, while a preferred embodiment of the clip and shingle construction has been described and illustrated herein in specific terms and details of structure and arrangement, various changes in and modifications of the same may be resorted to without departing from the spirit of the invention, or the scope of the claim appended hereto. 120

Having thus fully described the invention, 125 what is claimed, is:—

In a shingle roof construction, a series of equidistantly spaced parallel furring strips, shingles for disposition on said strips, each of said shingles having a longitudinally 130

central elongated slotway extending inwardly from its upper end edge and a lower end edge recess in alignment with the slotway, the lower portion of each shingle having one side edge cut away to form with an adjacent shingle a slotway, said shingles being disposed on said furring strips with the lower end edge recesses of one row superposed over the inner end of the side edge slotways of the next previous row and over the slot-

ways extending from the upper end edges of the third succeeding row whereby to form on a portion of each furring strip three layers of shingles, and clip members disposed through said end edge recesses, side edge 15 slotways and end edge slotways for binding the shingles on said furring strips.

BERNIE C. KRIDLER.
JAMES C. BOYLE.
